UNITED STATES PATENT OFFICE.

LLOYD V. LEWIS OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed April 9, 1927. Serial No. 182,344.

My invention relates to railway traffic controlling apparatus, and particularly to apparatus of the type comprising train carried governing means controlled by energy received from the trackway. More particularly my present invention relates to apparatus suitable for use on railways using electricity for propulsion and over which are operated multiple unit trains, that is, trains made up of a plurality of cars each provided with propulsion means and which cars may be combined in suitable numbers and operated from one of the cars to form a train of any desired length.

15 I will describe one form of railway traffic controlling apparatus embodying my invention, and will then point out the novel features thereof in claims.

In the accompanying drawings, Fig. 1 is 20 a diagrammatic view illustrating one form of trackway apparatus suitable for co-operation with train carried governing means embodying my invention. Figs. 2 and 3 are diagrammatic views which when placed end 25 to end with Fig. 2 on the left illustrate one form of train carried governing means embodying my invention, and adapted to co-operate with the trackway apparatus illustrated in Fig. 1. Fig. 4 is a bottom view 30 of the car G of Fig. 1 showing the location of receivers H¹ and H².

Similar reference characters refer to similar parts in each of the several views.

Referring first to Fig. 1, the reference 35 characters 1 and 1^a designate the track rails of a stretch of railway track over which traffic normally moves in the direction indicated by the arrow. These rails are divided by means of insulated joints 2, to form a 40 plurality of successive track sections A—B, B—C, etc. A suitable source of propulsion current, which in this case is assumed to be direct current, is connected between the rails and a propulsion conductor 15, such as a 45 trolley or third rail. The usual impedance bonds 4 are provided adjacent each pair of insulated joints 2 to conduct propulsion current past these joints.

Each track section is provided with a 50 trackway signal designated by the reference character S with an exponent corresponding to the location. These signals may be controlled by any suitable means forming no part of my present disclosure and omitted

from the drawing for the sake of simplicity. 55 For present purposes it is sufficient to state that each signal S is so controlled that when the associated section is occupied, the signal indicates stop, when the associated section is unoccupied and the section next in 60 advance is occupied, the signal indicates caution, and when the associated section and the section next in advance are both unoccupied, the signal indicates proceed. Associated with each signal S is a circuit controller 7 which is arranged to be closed only 65 when the signal indicates caution or proceed.

Means are also provided for supplying the rails of each section with alternating train controlling current. As here shown 70 the immediate source of such train controlling current is a transformer designated by the reference character D with an exponent corresponding to the location and having its secondary 5 constantly connected across 75 the rails adjacent the exit end of the corresponding section. The primary 6 of each transformer D is supplied with alternating current from secondary 8 of an adjacent line transformer T, over circuit controller 7 of 80 the signal S for the section next in advance. The primary 9 of each transformer T is constantly supplied with alternating current from a suitable source, such as an alternator M, over line wires 3 and 3^a. It follows therefore that the rails of each section are supplied with alternating train controlling current only when the signal for the section 85 next in advance indicates caution or proceed.

For a purpose which will appear herein- 90 after, each section is further provided with a reset loop designated by the reference character 12 and comprising two conductors located in the trackway adjacent the track rails, respectively, near the exit end of the 95 section. Each reset loop 12 is constantly supplied with alternating train controlling current from secondary 10 of an associated transformer E, the primary 11 of which is connected across the terminals of secondary 100 8 of the adjacent line transformer T.

It may become necessary at times to operate trains provided with governing means embodying my invention over portions of track which are not provided with means for 105 supplying the trackway with train controlling current. For example, the portion of track to the right of point C in the draw-

ing constitutes what I shall term "non-train control territory", to differentiate the territory to the left of point C which I shall term "positive train control territory". At 5 the entrance to non-train control territory I provide a "cut-out" loop 12^a which is constantly supplied with alternating train controlling current from secondary 13 of a transformer F, the primary 14 of which receives energy from secondary 8 of transformer T^c. The parts are so proportioned that the magnitude of the current flowing in the cut-out loop 12^a is considerably greater than the current supplied to the track rails 10 or to the reset loops in positive train control territory. This may be accomplished by constructing the transformer F with a secondary which delivers a higher electromotive force than the secondaries of transformers E and D which supply train controlling current to the trackway in positive train control territory. The purpose of the cut-out loop 12^a will be explained in detail hereinafter.

25 As has been suggested the trackway apparatus illustrated in Fig. 1 is suitable for cooperation with governing means located on separate cars of multiple unit trains. In systems of this character each of the cars is 30 provided with governing means which form a complete unit and it will therefore be sufficient to describe the apparatus located on a single car, it being understood that each of the remaining cars is provided with similar 35 apparatus and that any suitable number of cars may be operated from a single car in a train of any length.

In Fig. 1, the reference character G designates a car occupying the section to the left 40 of point A. It will be seen that this car is provided with two receivers H¹ and H², one located at each end of the car as best shown in Fig. 4, and each comprising two magnetizable cores 16 and 16^a carried in inductive 45 relation with the two track rails 1 and 1^a, respectively. Each core 16 is provided with a winding 17 and each core 16^a carries a similar winding 17^a, the windings 17 and 17^a of each receiver being connected in series in 50 such manner that the voltages induced therein by alternating train controlling current which flows in opposite directions in the two track rails from a source connected with the rails in advance of the car are additive. It 55 will be plain that since each receiver is responsive to energy supplied to the track rails from a source located in advance of the train the receiver must be located in advance of the forward axle of the car. As shown in 60 Fig. 1 train controlling current supplied to the rails of a section to the left of point A will energize receiver H¹, but this current will be shunted away from the receiver H² by the wheels and axles of the car G. If, 65 however, the car G were turned end for end,

receiver H² would be energized by the train controlling current and this current would be shunted away from receiver H¹. By providing two receivers therefore, it is possible to operate the car with either end of the car 70 as the "head-end".

Referring now to Figs. 2 and 3, I have shown the apparatus which is located upon a car which is provided with operating equipment by means of which the car may be controlled from either of two cabs located usually at opposite ends of the car. In multiple unit equipment of this type, each car is usually provided with two master controllers for governing the supply of motive 75 power to the car and with two brake valves for controlling the air brake applying equipment.

In my invention I provide governing means which is arranged to be placed under 80 the control of one or the other of the two receivers H¹ or H², depending upon which end of the car is operated as the "head-end". In order to make the selection, I provide two 85 directional relays K¹ and K² which are controlled by plug switches Y¹ and Y², respectively, on the master controllers which are located in the two cabs of the car. These 90 plug switches are a part of the usual standard equipment for multiple unit car control. Each switch comprises a pair of normally 95 open contacts arranged to be closed by the insertion of a plug carried by the operator of the car, for the purpose of energizing the power control circuits of the master controller into which the plug is inserted, so that 100 this master controller may be put into condition for controlling the car motors, while all other master controllers on the train will remain inactive because their plug switch 105 circuits will be open. In practice, the operator of the car inserts his plug in the master controller at the head end of the train prior to, and as a part of his preparation for, starting 110 a run, and removes it upon the completion of his run.

As shown in the drawing, the parts occupy the positions which they would assume if the car were being operated with the receiver H¹ at the head end. Under these 115 conditions plug switch Y¹ is closed and current flows from a suitable source of energy such as a battery X, through wires 20 and 21, plug switch Y¹, wires 22 and 23, contact 68 of an acknowledging switch L¹, wire 120 24, winding of relay K¹, and common wire 25 back to battery X. The function of the manually operable acknowledging switch L¹ is explained hereinafter and since contact 125 68 of this switch is normally closed, relay K¹ is energized by current over the circuit just traced so that the front contacts of this relay are closed.

When relay K¹ is energized, receiver H¹ is connected with a main relay R through 130

amplifying apparatus which I will now describe in detail.

Two three-element electron tubes 33 and 34 have their filaments supplied with energy 5 from battery X when relay K¹ is energized, the circuit for these filaments passing from battery X, through wires 20 and 21, plug switch Y¹, wires 22, 23 and 35, front contact 36 of relay K¹, wires 37, 38, 39, 40, 40^a and 10 41, filament of tube 34, resistance 42, filament of tube 33, resistance 43, and common wire 25 back to battery X. The common wire 25 is also connected through a resistance 59, with the ground. The purpose of resistances 42 and 43 is to adjust the filament current and also to provide the proper negative bias for the grid circuits of the electron tubes. One terminal of the receiver H¹ is connected through wire 69, and contact 32 15 of a manually operable cut-out switch O¹ with the common wire 25, and when relay K¹ is energized the other terminal of the receiver is connected with a point on an auto transformer, or reactor 31 through wire 26, 20 front contact 27 of relay K¹, wires 28 and 29 and a condenser 30. One terminal of the auto transformer 31 is constantly connected with the common wire 25. Under these conditions therefore, the receiver H¹ is connected 25 across the primary of the auto transformer 31 and its circuit is tuned by condenser 30. The secondary of transformer 31 is tuned by condenser 45 connected across its terminals, and the resonant voltage at the 30 terminals of condenser 45 is impressed through resistances 44 and 43 across the grid to filament circuit of tube 33. The condensers 30 and 45 and the transformer 31 constitute a filter which is so proportioned 35 that it excludes currents of frequencies other than those of the train controlling current thereby preventing false operation of the apparatus due to stray alternating currents of other frequencies. In multiple with the plate to filament circuit of tube 33 is a high 40 impedance circuit comprising a condenser 47 and a resistor 46, an intermediate point of which is connected with the grid of tube 34. In multiple with the plate to filament 45 circuit of tube 34 is an output circuit comprising condensers 49 and 50 and the primary of transformer 65. Condenser 49 is connected in series with primary 48 to prevent the flow of direct current through this 50 primary and also to choke out low frequencies, and condenser 50 is shunted across the primary 48 to tune it to the frequency of the train controlling current and to by-pass currents of a higher frequency than the train 55 controlling current. This output circuit is therefore a "filter" to discriminate against frequencies other than those of the train controlling current.

Energy is supplied to the plate circuits 60 of the tubes 33 and 34 from the propulsion

conductors of the railway. For this purpose I connect two regulator tubes 55 and 56 between the trolley or third rail collector 60 and the ground in a circuit which passes from the collector 60 through a limiting impedance 61, front contact 58 of a relay 57, wire 62, winding of a relay 53, wire 63, regulator tubes 55 and 56 and wire 64 to ground. Each of the tubes 55 and 56 has the characteristic of maintaining constant 70 the voltage drop across its terminals irrespective of the current through the tube, and hence this voltage is within limits, independent of the voltage between the third rail or trolley, and ground. One form of 75 device which will operate in the manner described comprises a tube containing a relatively large cathode and a small anode in an atmosphere of neon gas and a small quantity of an alkali metal. The constant electromotive force across the terminals of tubes 80 55 and 56 neglecting the relatively small drop across low resistance relay 53, is applied to the plate circuits of tubes 33 and 34 through reactors 51 and 52 and a front 85 contact 54 of relay 53. The purpose of relay 53 is to discontinue the supply of energy to the plate circuits of the amplifier tubes if the circuit through the tubes 55 and 56 should become open so that they would fail 90 to limit the voltage supplied to the plate circuit. The relay 57 is constantly connected with wires 39 and 25, and this relay is therefore energized only when relay K¹ is energized, that is, when plug switch Y¹ and 95 contact 68 of switch L¹ are closed. It will therefore be plain that the tubes 33 and 34 are connected to form a choke coil coupled 100 amplifier of the usual and well known form, so that the current supplied to primary 48 of transformer 65 is controlled in accordance with the energy supplied from receiver H¹. The secondary 66 of transformer 65 has its mid-point connected with one terminal of the direct current relay R and the other 105 terminal of this relay is connected with the two terminals of the secondary 66 through a pair of oppositely disposed rectifiers 67. It follows that when the parts occupy the 110 positions illustrated in the drawing and when the car is receiving train controlling current from a point in advance of the receiver H¹, relay R is energized but that when such supply of train controlling current is interrupted, relay R becomes de-energized. 115 When relay R is picked up, current flows from battery X, through wires 20 and 21, plug switch Y¹, wires 22, 23 and 35, front contact 36 of relay K¹, wires 37, 38, 39, 40 and 70, front contact 71 of relay R, wires 72, 73 and 74, front contact 75 of relay K¹, wires 76 and 77, lamp 78 of cab indicator N¹ and common wire 25 back to battery X. Lamp 78 is therefore lighted to indicate 120 "proceed".

Relay R controls a magnet valve V¹ comprising a stem 81 which connects pipe 84 with a suitable source of fluid pressure not shown in the drawing through pipe 82 when 5 the magnet valve is energized. When magnet valve V¹ is de-energized, the stem 81 moves to its reverse position, thereby disconnecting pipe 84 from pipe 82 and connecting pipe 84 with pipe 83. Pipe 83 communicates with atmosphere through a restricted orifice 83^a. Connected with pipe 83 between the orifice 83^a and valve V is a fluid pressure operated audible signal here illustrated as a whistle 149. Pipe 84 is connected, through a restricted orifice 84^a bypassed by a check valve 86, with a timing reservoir 85 and a timing valve 87.

The timing valve 87 comprises a diaphragm 89, the underside of which is subjected to pressure in the timing reservoir 85. A valve stem 90 is operated by the diaphragm 89 and is biased by a spring 93, to a lower position in which pipe 91 is connected to pipe 92. When the timing reservoir 85 and pipe 84 are charged with fluid pressure, as when valve V¹ is energized, diaphragm 89 moves upwardly, lifting stem 90 to close the connection from pipe 91 to pipe 92, and connecting the stop reservoir 30 via pipe 92 with atmosphere through pipe 88.

The timing valve 87 controls an application valve Q¹ comprising a piston 96 provided with a restricted orifice 96^a. Valve 35 Q control the usual automatic brake applying apparatus on the train in such manner that when the valve moves from its normal to its reverse position an automatic application of the brakes results. One branch 91^a 40 of pipe 91 communicates with the lower piston chamber of valve Q¹. When pipe 91 is blanked, fluid pressure admitted to the upper chamber of valve Q¹ through pipe 102 passes through the orifice 96^a and equalizes 45 the fluid pressure on both sides of the piston, permitting spring 154 to hold the piston 96 in its normal position as shown in the drawing. When valve Q is in this position, branch 91^b of pipe 91 is blanked, but when 50 valve Q reverses, this branch 91^b is connected with pipe 95 through the port 99 in valve Q¹. Pipe 95 is connected at times with atmosphere through port 98 in the rotary valve of the motorman's brake valve, and 55 pipe 97. The port 98 is normally open to atmosphere and is closed only when the brake valve occupies the lap position or the handle off position. It follows that port 98 is usually open in an operative brake valve as indicated in Fig. 3, and port 98 is blanked in an inoperative brake valve, as at the opposite end of the car and as shown in Fig. 2.

Associated with valve Q¹ is a pneumatic relay designated by the reference character 60 P¹ and comprising a plunger 106 controlled

by a diaphragm 105 which is responsive to the pressure in pipe 104. Pipe 104 is normally connected with atmosphere through cavity 100 of valve Q¹ and port 103, and under this condition all of the contacts of 70 relay P are closed.

One purpose of pneumatic relay P¹ is to cut off the motive power of the car when the brakes are applied automatically, in such manner as to prevent the operator from obtaining power for forward running, but so as to not prevent him from energizing the car motors in reverse for dynamic braking in the event of an emergency. The master control circuit of the multiple unit control 75 system comprises a number of wires running the length of the train, two of which must be separately energized from the master controller to obtain power.

One of these wires, marked "AB+" 80 controls a circuit breaker on each car, arranged to open if its circuit is momentarily interrupted, and when open to close again only after a return of the master controller handle to the neutral or "handle-off" position. 90 This circuit breaker wire is closed over contact 133 of relay P¹ in both the lower and upper positions of plunger 106, but is open at mid-stroke. Relay P¹ is provided with a compressible spring stop 175 adjusted to 95 engage plunger 106 at mid-stroke. When the brake application valve Q¹ reverses, pipe 104 is connected through a port 101 with the source of pressure 102, and the diaphragm and plunger of P¹ will therefore lift as soon as this pressure builds up sufficiently to overcome the return spring 174, but will pause in mid-stroke with contact 133 open for a short time until the pressure has built up sufficiently to overcome the combined pressure of spring 174 and of spring stop 175 whereupon plunger 106 will complete its stroke to again close contact 133.

A second master control circuit J¹ must be closed for forward running. When P¹ is supplied with pressure J¹ is opened by contact 135. The corresponding wire J², which must be closed for reverse running is not controlled over P¹. When the car is operated from the opposite end these conditions are reversed, and so a brake application initiated by valve Q², of Fig. 2 operates relay P² to open the circuit of wire J², but not that of J¹.

It follows, therefore, that when valve Q¹ 120 reverses to cause an automatic brake application, as will be described hereinafter, the circuits AB+ and J¹ are opened to cut off power to the car motors. After a brief interval of time plunger 106 completes its 125 stroke and circuit AB+ is again closed, but circuit J¹ remains open. The motorman may then move his controller handle to neutral to re-energize his circuit breaker over AB+, and since J² is not affected by opera- 130

tion of P^1 , he may then reverse his controller to energize the motors in reverse for dynamic braking. It should be noted, however, that since circuit J^1 is now open, the motorman 5 can not operate the motors for forward running. The control of circuits AB+ and J^2 by relay P^2 is similar to the control of circuits AB+ and J^1 by relay P^1 , and will be understood without further explanation, it 10 being remembered that when the car is being operated with the apparatus shown on Fig. 2 at the head end, circuit J^2 is used for forward running, and circuit J^1 for reverse running.

15 The valve V^1 is controlled by a circuit which is closed when relay R is energized. This circuit may be traced from battery X, through wires 20 and 21, plug switch Y^1 , wires 22, 23, and 35, front contact 36 of relay K^1 , wires 37, 38, 39, 40 and 70, front contact 71 of relay R, wires 72 and 107, back contact 108 of relay 121, wire 109, back contact 110 of relay 122, wire 111, winding of polarized relay 112, wires 113 and 114, front 25 contact 115 of relay K^1 , wire 155, winding of magnet valve V^1 , wires 116 and 117, back contact 118 of relay 122, wire 119, back contact 120 of relay 121 and common wire 25 back to battery X. When this circuit is 30 closed, magnet valve V^1 occupies its normal position so that fluid pressure from pipe 82 flows through valve V^1 , pipe 84 and check valve 86 to the timing reservoir 85. The timing valve 87 therefore occupies its normal 35 position so that pipe 91 is blanked and the stop reservoir 94 is connected with atmosphere through pipe 88. Valve Q^1 occupies its normal position so that the brakes are released and pneumatic relay P^1 is connected with atmosphere so that all the contacts of this relay are closed. Under these 40 conditions the train can proceed without restriction.

If, however, relay R becomes de-energized, 45 lamp 78 is immediately extinguished and a circuit is closed for lamp 79 from battery X, through wires 20 and 21, plug switch Y^1 , wires 22, 23 and 35, front contact 36 of relay K^1 , wires 37, 38, 39, 40 and 70, back 50 contact 71 of relay R, wires 123 and 124, back contact 125 of relay 122, wires 125^a, 126 and 127, front contact 128 of relay K^1 and wires 129 and 129^a through lamp 79 to common wire 25. At the same time the 55 opening of front contact 71 of relay R interrupts the circuit just traced for valve V^1 so that this valve reverses, closing the supply pipe 82, and connecting pipe 84 to pipe 83. The fluid pressure with which timing reservoir 60 85 had been charged is then discharged through the orifice 83^a to atmosphere and through the whistle 149, thereby positively calling the attention of the operator to the change in traffic conditions. If traffic conditions 65 remain unchanged, and if the operator

takes no action, it follows that after the expiration of a fixed time interval the pressure in reservoir 85 and hence below diaphragm 89 of timing valve 87 will be so reduced that the spring 93 will move the stem 90 to its reverse position, thereby connecting pipe 91 with pipe 92, and hence with the empty stop reservoir 94. This connection reduces the pressure in valve Q^1 beneath piston 96 and the unbalanced pressure above the piston 70 then moves the valve to its reverse position. Branch 91^b of pipe 91 is then connected with pipe 95 and hence with atmosphere through port 98 of the brake valve. The reversal of valve Q^1 causes an automatic application of 75 the brakes which cannot be released until the operator moves the brake valve to the lap position to close port 98. When the operator closes port 98, fluid pressure from source 102 flows through port 96^a in piston 80 85 96 and after a time interval which is usually made sufficient to insure that the train will be brought to a stop, builds up the pressure in pipes 91, 95 and 92 and in the stop reservoir 94, so that the force exerted on the lower 90 side of piston 96 by the fluid pressure and the spring 154 exceeds the force exerted by the fluid pressure above this piston and causes valve Q^1 to be returned to its normal 95 position. When the valve Q^1 moved to its reverse position pneumatic relay P^1 was reversed, and this relay is restored to its normal position when valve Q^1 returns to normal. Of course contact 133 opens for a brief interval during the restoration of relay P^1 to its normal position, but since the car is at rest when P^1 is restored, the motorman's master controller will then be in the neutral position, so that the brief opening of contact 133 will not trip the circuit breakers. 100 After valve Q^1 and relay P^1 have returned to their normal positions, then, the motorman may immediately operate his controller 105 to start the car.

If now the signal changes to "clear" after 110 the brakes start to apply, magnet V^1 picks up and charges reservoir 85 quickly through check valve 86 causing the timing valve to lift to close port 91. If the operator now moves his brake valve to lap position, he 115 may obtain a release of the brakes almost at once, because valve Q will restore to normal as soon as the comparatively small volume of pipes 91^a and 91^b and that portion of pipe 95 above check valve 173 are 120 charged.

The operator of the car can prevent an 125 automatic application of the brakes due to de-energization of relay R if he takes proper action when the necessity for such action is called to his attention by the lighting of lamp 79 and the blowing of whistle 149. To prevent such an automatic application of the brakes, after relay R becomes de-energized to reverse valve V^1 , and before valve 130

87 reverses, the operator reverses the acknowledging switch L^1 to close contact 131. Current then flows from battery X , through wires 20 and 21, plug switch Y^1 , wires 22, 23, and 35, front contact 36 of relay K^1 , wires 37, 38, 39, 40 and 70, back contact 71 of relay R , wires 123 and 124, back contact 125 of relay 122, wires 125^a, 126 and 127, front contact 128 of relay K^1 , wires 129 and 130, contact 131 of acknowledging switch L^1 , wire 132, contact 134 of pneumatic relay P^1 , wires 136, 137 and 138, winding of relay 121 and common wire 25 back to battery X . It should be pointed out that this pick-up circuit includes a contact on the pneumatic relay P^1 and it follows that the acknowledging relay 121 can be energized only if the acknowledging switch L^1 is operated prior to the reversal of relay P^1 . As soon as relay 121 becomes energized a branch or stick circuit is closed for this relay from back contact 71 of relay R , wires 123 and 124, back contact 125 of relay 122, through wires 125^a and 140 front contact 141 of relay 121, wires 142 and 138, winding of relay 121, back to common wire 25. After relay 121 has once been picked up, therefore, it is subsequently maintained in its energized condition as long as relay R is de-energized and relay K^1 is energized. But relay K^1 is controlled by contact 168 of the acknowledging switch L^1 , which contact was opened when the switch was operated to close contact 131 to pick up relay 121. As soon as the acknowledging relay 121 has become energized, therefore, the operator should return the acknowledging switch L^1 to its normal position, thereby again completing the circuit for relay K^1 . Due to the slow acting characteristics of the directional relays K^1 and K^2 , these relays will bridge the brief time interval during which their circuits are opened by operation of the corresponding acknowledging switch. When relay 121 is energized, an auxiliary circuit is closed for the valve V^1 which maintains the valve in its normal position provided the speed of the train does not exceed a predetermined value. In the form here shown this speed control is accomplished by means of a speed responsive device designated in general by the reference character U and comprising a centrifuge 143 of any suitable type geared to an axle of the car. The centrifuge 143 controls two contacts 144 and 145 which contacts are normally closed but are arranged to be opened when the speed of the train exceeds a predetermined value. When relay 121 is energized the contacts 144 and 145 are inserted in series with the valve V^1 , the complete circuit passing from battery X , through wires 20 and 21, plug switch Y^1 , wires 22, 23 and 35, front contact 36 of relay K^1 , wires 37, 38, 39, 40, 40^a and 146, contact 144 of device U , wire 147, front contact 108 of relay 121, wire 109, back contact 110 of relay 122, wire 111, polarized relay 112, wires 113 and 114, front contact 115 of relay K^1 , wire 155, winding of valve V^1 , wires 116 and 117, back contact 118 of relay 122, wire 119, front contact 120 of relay 121, wire 148, contact 145 of device U and common wire 25 back to battery X . It follows therefore that as long as relay 121 is energized, valve V^1 is held in its normal position providing the speed of the car does not exceed that value at which the contacts of the speed responsive device U will open. Should the speed of the car exceed this value, the circuit for valve V^1 will remain opened, the warning whistle will blow and the brakes will be automatically applied.

If, however, after relay R has become de-energized and the operator has acknowledged to permit the car to proceed at a restricted speed, relay R should again become energized, relay 121 will drop to establish the circuit first traced for valve V^1 , thereby eliminating the speed responsive device U from the control of this valve and restoring the apparatus to its normal condition.

When the car proceeds into non-train control territory, the interruption of the supply of train controlling current to the car of course results in the de-energization of relay R . In the absence of any preventative means this would result in an automatic application of the brakes or restrict the train to a low speed and it is therefore desirable to provide apparatus for permitting the operator to "cut out" the train carried governing means when the car enters non-train control territory. It is for this purpose that the cut-out loop 12^a is provided at the entrance to the non-train control territory as described in connection with Fig. 1. If the operator wishes to cut out as he enters non-train control territory he operates the cut-out switch O^1 while the receiver is over the cut-out loop 12^a. When switch O^1 is operated, the opening of contact 32 introduces a resistor 172 in series with the receiver, in this case H^1 , which is connected with the relay R . The value of the resistor 172 is such that the energy supplied to the receiver in accordance with the magnitudes of train control current supplied to the trackway in train control territory by the normal track circuits or the re-current acknowledging loops is not sufficient to operate relay R through the resistor 172. Operation of the switch O^1 in positive train control territory in an attempt to cut out the control in such territory will, therefore result in de-energization of relay R and a consequent application of the brakes, though the motorman may prevent such automatic application by operation of switch L^1 , provided the car speed is so low that the contacts of speed responsive device U are closed. When the receiver is over a cut-out loop 12^a, the ab-

normally large current in the cut-out loop supplies sufficient energy to the receiver to maintain relay R in its energized condition even though switch O¹ is operated to introduce the resistor 172 in the receiver circuit. When switch O¹ is operated while the receiver is over the cut-out loop, a pick-up circuit including one winding a of the cut-out relay 122 is closed, current flowing from battery X, through wires 20 and 21, plug switch Y¹, wires 22, 23 and 35, front contact 36 of relay K¹, wires 37, 38, 39, 40 and 70, front contact 71 of relay R, wires 72, 73 and 74, front contact 75 of relay K¹, wires 76 and 150, contact 151 of cut-out switch O¹, wires 152, 152^a and 153, winding a of relay 122, and common wire 25 back to battery X. Relay 122 therefore picks up, extinguishing lamp 78 and opening the normal circuit first traced for valve V¹. Valve V¹ is not reversed, however, because a second circuit is closed for this valve from battery X, through wires 20 and 21, plug switch Y¹, wires 22, 23 and 35, front contact 36 of relay K¹, wires 37, 38 and 156, contact 157 of an inspector's switch W, wire 158, front contact 118 of relay 122, wires 117 and 116, winding of valve V¹, wire 155, front contact 115 of relay K¹, wires 114 and 113, winding of polarized relay 112, wire 111, front contact 110 of relay 122, and common wire 25 back to battery X. Valve V¹ is therefore energized over this new circuit, but it should be observed that the direction of current through the polarized relay 112 is opposite to the direction of the current through this relay when the normal circuit for valve V¹ is closed. Contact 160 of relay 112 which contact is normally open is therefore closed when the operator cuts out by energizing relay 122. When the car passes off the loop 12^a, relay R becomes de-energized, but relay 122 remains closed, as will be explained hereinafter, and a circuit is closed for lamp 80 of indicator N¹ from battery X, over wires 20 and 21, plug switch Y¹, wires 22, 23 and 35, front contact 36 of relay K¹, wires 37, 38, 39, 40 and 70, back contact 71 of relay R, wires 123 and 159, contact 160 of relay 112, wires 161 and 162, front contact 169 of relay K¹, wire 170, and lamp 80 through common wire 25 back to battery X. The lighting of lamp 80 informs the operator that the train carried apparatus is cut out and also that the train has passed over the cut-out loop. The operator therefore restores the cut-out switch O¹ to its normal position, thereby completing a holding circuit for relay 122 which is the same as the circuit just traced for lamp 80 as far as wire 162 from which wire current flows through wire 163, front contact 164 of relay K¹, wire 165, contact 166 of cut-out switch O¹, wires 167 and 168, winding b of relay 122 and common wire 25 back to battery X. This holding circuit is closed only when relay R is de-energized, when relay K¹ is energized and when the cut-out switch O¹ occupies its normal position. Relay 122 is sufficiently slow acting to hold its front contacts closed during the transit of contact 166 from its open to its closed position. After the relay 122 has once been energized, therefore, it is subsequently maintained in its energized condition by virtue of the holding circuit just traced as long as relay R remains de-energized. After the apparatus has been cut out, should the car again enter positive train control territory, the supply of train controlling current to the track rails would energize relay R, thereby interrupting the holding circuit for relay 122, allowing this relay to open, and restoring the apparatus to its normal condition.

In describing the operation of the apparatus as a whole, I will assume that a car equipped with the devices illustrated in Figs. 2 and 3 and with the apparatus in the condition there shown proceeds through the stretch of track shown in Fig. 1. In Fig. 1 signals S^A, S^B and S^C all indicate proceed. Train controlling current is therefore supplied to the rails of each section of the positive train control territory. As the car G proceeds through the stretch of track to the left of point C, relay R is energized so that lamp 78 is lighted to indicate proceed and valve V¹ is energized so that the application valve Q¹ occupies its normal position and the brakes are released.

I will next assume that signal S^B is at stop so that the supply of train controlling current to the rails of section A—B is interrupted. The recurrent acknowledgment loop 12 adjacent point B is energized, however. Under these conditions when the car G enters section A—B, the interruption of train controlling current de-energizes relay R, extinguishing lamp 78 and lighting lamp 79. Furthermore the de-energization of relay R will break the circuit for valve V¹ and will cause an automatic application of the brakes unless the operator manipulates the acknowledging switch L¹ to energize relay 121. If the operator does acknowledge, the train will be permitted to proceed through section A—B at a speed not exceeding that speed at which the device U will open contacts 144 and 145. When the car reaches the loop 12 the alternating current in this loop will again energize relay R, thereby interrupting the stick circuit for relay 121, and allowing the latter relay to become de-energized. After the train has passed the loop 12, relay R will again become de-energized and it will be necessary for the operator to again operate the acknowledging switch L¹ in order to re-energize relay 121 to prevent an automatic application of the brakes.

Assuming that all of the parts occupy the positions shown in Fig. 1, when the car G passes point C, the operator should manipulate the cut-out switch O^1 to cut out his apparatus. If he does not take such action the relay R will become de-energized when the train has passed beyond the loop 12^a and an automatic application of the brakes will result. Of course the operator could manipulate the acknowledging switch L¹ to prevent this automatic application of the brakes. But it should be remembered that the closing of relay 121 imposes a restricted speed limit upon the car and in order to prevent the imposition of this speed limit the operator must cut out upon entering non-train control territory. If he does cut out as the car passes over the cut out loop 12^a, the relay 122 becomes energized as has been explained in detail hereinbefore, and the operator may then proceed with his car with no restrictions upon his speed.

During all of the preceding explanation I have assumed that the plug switch Y¹ is closed and the car is being operated with the head-end corresponding to the end which carries the receiver H¹. It is of course necessary to operate the car in the opposite direction, and it is sometimes desirable even to operate the car in the same direction from the cab located at the rear of the car. It is also desirable at times to operate the car as a "trailer" car in a train of two or more cars, with the train control equipment inactive and ineffective, yet in such condition that it may be put into operation whenever the car is to be used as a head car, merely by the insertion of the operator's plug into switch Y¹ or Y². With this explanation in mind it should be pointed out that by the operation of the plug switches Y¹ and Y² controlling the directional relays K¹ and K², respectively, relay R and the apparatus associated therewith is placed under the control of receiver H¹ or receiver H² according as the train is proceeding in one direction or the other. The apparatus controlled by the relays R, 121, 122 and 112 is duplicated at each end of the car, and the operation of the apparatus when plug switch Y² is closed to operate the car from the end corresponding to receiver H² will be manifest from the foregoing explanation. It is sufficient here to state that when directional relay K² is energized, relay R is controlled through the amplifier tubes 33 and 34, by energy received from H². Under these conditions also, valves V² and Q² are controlled by relay R and the operator controls valve V² by means of switches L² and O² in a manner similar to the control of valve V¹ by switches L¹ and O¹.

When the operator leaves the car at the end of a run, he first places his brake valve

in the handle-off position, thereby closing port 98 of this valve, and removes the brake valve handle. He then removes the plug from his master controller thereby opening plug switch Y associated with such controller. This of course de-energizes the associated directional relay K, disconnecting the receiver from the relay R and causing relay R to become de-energized. The circuit for the corresponding valve V is therefore opened and the corresponding valve Q is reversed to cause an automatic application of the brakes. The stop reservoir 94 then becomes charged and after a time interval sufficient to insure a full service brake application, restores valve Q to its normal position. This is the normal inactive condition of the pneumatic equipment and is the condition in which the apparatus located on the left-hand end of car (Fig. 2) is illustrated in the drawing. It is to be understood, however, that this movement of valve Q to normal position does not release the train brakes, for the reason that all brake valves of the train are under the condition specified, in the "handle-off" position in which all ports in the rotary valve are blanked; therefore, the brake pipe will remain at reduced pressure and will not be recharged. When the operator undertakes to start the train from the opposite end for his return trip, or from any other control position he inserts his brake valve handle in the brake valve, and the plug in switch Y at the control position in question. This picks up relay K, which energizes his train control equipment as evidenced by the lighting of cab lamp 80. When relay 122 picks up (assuming contact 160 of relay 112 closed, as hereinafter described) it energizes magnet V which in turn energizes the timing valve and closes pipe 91, so that he can move his brake valve away from the lap position without reversing valve Q. He then may release and recharge his brake equipment in the usual manner and proceed to the entrance of train control territory.

If the operator should fail to insert his plug, or if he should insert his plug and magnet V failed to pick up, or if the timing valve should fail to close port 91 and vent stop reservoir 94 to atmosphere, any movement of his brake valve away from the "handle-off" position would open pipe 95, and hence pipe 91, to atmosphere and cause valve Q to reverse to cause a reapplication of the brakes which in turn would cause relay P to reverse to cut off his power. In other words the automatic train control equipment is self-checking, so that an operator cannot control the train from any control position unless the automatic equipment is energized and in condition to operate if de-energized, while the similar equipment at each of the

other control positions in the train does not interfere with his manual control and is inoperative although it is de-energized.

The polarized relay 112 is preferably arranged with a hardened steel core so that the armature 160 of this relay remains in the position to which it was last moved until the relay is energized in the opposite directions to positively reverse the armature. It follows that when the apparatus is once cut out, if the operator opens the plug switch Y, the contact 160 will remain closed to the left. If now the car is again used as head car of a train, as soon as the engineman inserts his plug in his master controller, his directional relay K will pick up, thereby completing the circuit for winding b of the cut-out relay 122 and again placing the apparatus on the train in the cut-out condition. Of course this result will be accomplished only if the apparatus was cut out when the operator left the train. The normal condition of relay 112 in non-train control territory and also on all cars of the train except the head car within train control territory, is with contact 160 closed, and this contact will open only on the head car of a train upon entering train control territory and will be closed again when the train leaves such territory if the cut-out switch is properly operated. In order to insure that the relays 112 on all cars of the train are in their proper condition, each car is provided with an inspector's switch W. When the cars are assembled in a train at the terminal, an inspector goes through the train, and inserts his plug in a master controller on each car, observing whether or not the lamp 80 becomes lighted. If this lamp does light it indicates that the relay 112 is energized in the proper direction to permit relay 122 to pick up, since the lamp 80 can be energized only when contact 160 of relay 112 is closed. If, when the inspector inserts his plug in the master controller, the lamp 80 does not light, he operates the inspector's switch W, thereby connecting wire 39 with wire 153 through contact 171 of the switch. This operation energizes relay 122. When the inspector's switch is restored to its original position to again close contact 157, a circuit is completed through relay 112 and the valve V over which current flows in such direction as to close contact 160 of relay 112. The cut-out relay 122, of course, remains in its energized condition until the plug switch Y¹ or Y² is opened. The inspector is informed by the lighting of lamp 80 that the apparatus has been placed in its proper condition. Although I have herein shown and described only one form of railway traffic controlling apparatus embodying my invention, it is understood that various changes and modifications may be made therein within the scope of the appended claims without de-

parting from the spirit and scope of my invention.

Having thus described my invention, what I claim is:

1. In combination, a railway car provided with two sets of operating equipment, two receivers, two relays one associated with each such set of equipment and each arranged to be energized only when the car is being operated from the corresponding set of equipment, and governing means controlled by one said receiver when one relay is energized and by the other receiver when the other relay is energized. 70
2. In combination, a railway car provided with two relays, means under the control of the car operator for energizing one or the other of said relays, governing means on the car, two receivers on the car, and means controlled by said two relays for selectively connecting said receivers with said governing means. 75
3. In combination, a railway car provided with a receiver, a first relay, means under the control of the car operator for energizing the first relay, a main relay connected with the receiver only when the first relay is energized, and governing means controlled by the main relay. 80
4. In combination, a railway car provided with a receiver, a first relay, means under the control of the car operator for energizing the first relay, a main relay connected with the receiver when the first relay is energized, and governing means controlled by the main relay and by said first relay. 85
5. In combination, a railway car provided with a receiver, a first relay, means under the control of the car operator for energizing the first relay, a main relay connected with the receiver when the first relay is energized, a manually operable acknowledging switch, an acknowledging relay controlled by the first relay, the main relay and the acknowledging switch, and governing means controlled by the acknowledging relay and by said main relay. 90
6. In combination, a railway car provided with a receiver, a first relay, means under the control of the car operator for energizing the first relay, a main relay connected with the receiver when the first relay is energized, a manually operable acknowledging switch, an acknowledging relay controlled by the first relay, the main relay and the acknowledging switch, and governing means controlled jointly by said three relays. 105
7. Railway traffic controlling apparatus for multiple unit trains comprising on each car two directional relays, means effective when the car is being operated with one end as the "head end" to energize one of the directional relays, means effective when the car is being operated with the other end as the head end to energize the other directional 110

- 125
- 130

relay, a main relay, two receivers one associated with each directional relay and each connected with the main relay when the associated directional relay is energized, and 5 governing means controlled by said main relay.

8. In combination, a railway car provided with a receiver, a first relay, means under the control of the car operator for energizing 10 the first relay, a main relay connected with the receiver when the first relay is energized, a manually operable acknowledging switch; an acknowledging relay controlled by the first relay, the main relay and the 15 acknowledging switch; means on the car for causing an automatic application of the brakes when the main relay is deenergized, and means for preventing such automatic application when the acknowledging relay 20 is energized.

9. In combination, a railway car provided with a receiver, a first relay, means under the control of the car operator for energizing the first relay, a main relay connected 25 with the receiver when the first relay is energized, a manually operable acknowledging switch; an acknowledging relay controlled by the first relay, the main relay and the acknowledging switch; means on the car 30 for causing an automatic application of the brakes when the main relay is de-energized, and means for preventing such automatic application when the acknowledging relay is energized provided the speed of the car is 35 below a predetermined maximum.

10. In combination, a railway car provided with a first relay, manually operable means for at times energizing the first relay, a main relay, a receiver connected with 40 the main relay when the first relay is energized, a manually operable acknowledging switch; an acknowledging relay controlled by the first relay, the main relay and the acknowledging switch; a contact responsive 45 to the speed of the car; and governing means controlled by the main relay, the acknowledging relay and the contact.

11. In combination, a railway car provided with a first relay, manually operable 50 means for at times energizing the first relay, a main relay, a receiver connected with the main relay when the first relay is energized, and a cab indicator controlled by said main relay and by said first relay.

55 12. In combination, a railway car provided with a first relay, means under the control of the operator for at times energizing the first relay, a main relay, a receiver for controlling the main relay in accordance 60 with energy received from the trackway when the first relay is energized, brake applying apparatus controlled by the main relay, and a cutout relay controlled in part by the first relay for at times removing the

main relay from the control of the brake 65 applying apparatus.

13. In combination, a railway car adapted to be operated with either end as the head end, two receivers located at the two ends of the car, respectively and both in inductive 70 relation with the track rails, a main relay on the car, means effective when the car is being operated with either end as the head end to place the main relay under the control of the receiver adjacent such end of the 75 car, and means controlled by said relay for governing the supply of motive power to the car.

14. In combination, a railway car adapted to be operated with either end as the head 80 end, two receivers located at the two ends of the car, respectively and both in inductive relation with the track rails, a main relay on the car, means effective when the car is being operated with either end as the 85 head end to place the main relay under the control of the receiver adjacent such end of the car, and means controlled by the main relay for at times preventing forward but not backward moves of the car. 90

15. In combination, a railway car comprising a normally energized device arranged to become de-energized under unsafe traffic conditions, and means operating to prevent the supply of motive power to the 95 car for forward moves but not for backward moves when said device is de-energized.

16. In combination, on an electric railway, a car provided with a relay, a receiver 100 for controlling the relay in accordance with energy received from the trackway, an amplifier interposed between the receiver and the relay and means for supplying said amplifier with energy from the railway 105 propulsion conductors.

17. In combination on an electric railway, a car provided with a main relay, a receiver for controlling the relay in accordance with energy received from the trackway an electron tube amplifier interposed between the 110 receiver and the relay, and means for supplying the plate circuit of said electron tube with energy from the propulsion conductors of the railway. 115

18. In combination on an electric railway, a car provided with a main relay, a receiver for controlling the relay in accordance with energy received from the trackway, an electron tube amplifier interposed between the 120 receiver and the relay, a device connected with the propulsion conductors of the railway and having the characteristic of maintaining constant the electromotive force across its terminals, and means for applying the electromotive force across the terminals of said device to the plate circuit of the 125 vacuum tube amplifier.

19. In combination on an electric railway, a car provided with a main relay, a receiver for controlling the relay in accordance with energy received from the trackway, an electron tube amplifier interposed between the receiver and the relay, a device connected with the propulsion conductors of the railway and having the characteristic of maintaining constant the electromotive force across its terminals, means for applying the electromotive force across the terminals of said device to the plate circuit of the vacuum tube amplifier, and means for automatically disconnecting the device from the plate circuit when the current through the device is below a predetermined value. 65
20. In combination on an electric railway, a car provided with a receiver responsive to energy received from the trackway, an electron tube having its grid circuit supplied with energy by the receiver, a source of energy for supplying current to the filament of said tube, means for supplying energy to the plate circuit of the tube when the electromotive force of said source is above a predetermined value, and a relay controlled by the plate circuit of the tube. 70
21. In combination, a railway train provided with brake applying apparatus, a plurality of brake valves, a single brake valve handle capable of use with any one of said brake valves to control said apparatus, a plurality of automatic means for controlling said apparatus one associated with each said valve, means associated with each automatic means for rendering such means ineffective to control the brakes, and means for actuating said apparatus when any one of said valves is operated by such handle unless the associated automatic means is in its effective condition. 75
22. In combination, a railway train provided with air brakes, a plurality of brake valves each normally occupying its handle-off position each capable of movement away from its handle-off position to control said brakes, a plurality of normally ineffective automatic means one associated with each said valve, means for rendering any one of said automatic means effective to control said brakes in accordance with traffic conditions, and means effective if any said valve is moved away from its handle-off position to apply the brakes if the corresponding automatic means is in its ineffective condition. 80
23. In combination, a railway train provided with air brakes, automatic means normally ineffective to control said brakes, manually operable means for rendering said automatic means effective to control the brakes in accordance with traffic conditions, and other manually operable means effective when and only when the automatic means is in its effective condition to control said brakes. 85
24. In combination, a railway train provided with air brakes, a plurality of brake valves each normally occupying a handle-off position and capable of movement away from such handle-off position to control said brakes, a plurality of automatic means one associated with each brake valve for controlling said brakes in accordance with traffic conditions, and means for causing any one of such automatic means to apply the brakes and to subsequently assume an ineffective condition provided the associated brake valve is in its handle-off position. 90
25. In combination, a railway train provided with air brakes, a plurality of brake valves each normally occupying a handle-off position and capable of movement away from such handle-off position to control said brakes, a plurality of automatic means one associated with each brake valve for controlling said brakes in accordance with traffic conditions, manually operable means for causing any one of such automatic means to apply the brakes, and means for subsequently rendering such automatic means ineffective provided the associated brake valve is in the handle-off position. 95
26. In combination, a railway train provided with air brakes, a plurality of brake valves each normally occupying a handle-off position, a single brake valve handle capable of use with any one of said valves to control said brakes, a plurality of application valves one associated with each said brake valve and each having a normal and a reverse position and operating in the reverse position to apply the brakes on the train, manually operable means for reversing any one of such application valves, and means effective upon the expiration of a time interval after such reversal to restore the application valve to its normal position provided the associated brake valve occupies its handle-off position. 100
27. In combination, a railway train provided with brake applying apparatus, a plurality of sets of automatic equipment, a manually operable device associated with each set of automatic equipment for controlling such apparatus and each having an ineffective position, means for rendering a selected one of such sets effective to control the brake applying apparatus in accordance with traffic conditions, and means controlled by each device for applying the brakes if the device is moved away from such ineffective position unless the associated set is in its effective condition. 105
